(57) **CLAIM**

The ornamental design for a molded pulp cup lid, as shown and described.

DESCRIPTION

FIG. 1 is a first perspective view of the molded pulp cup lid showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof;

FIG. 9 is an enlarged section view thereof, taken along line 9-9 of FIG. 6;

FIG. 10 is a first reference view when in use thereof; and, FIG. 11 is an enlarged second reference view when in use, taken along line 11-11 of FIG. 10.

The broken line showing in the drawings is included for the purpose of illustrating unclaimed portions of the molded pulp cup lid and forms no part of the claimed design.

1 Claim, 8 Drawing Sheets
